E. R. HOLMES

NARROW WARE LOOM

Filed July 12, 1921

UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

NARROW-WARE LOOM.

Application filed July 12, 1921. Serial No. 484,196.

To all whom it may concern:

Be it known that I, ELBRIDGE R. HOLMES, a citizen of the United States, residing at Worcester, in the county of Worcester and 5 State of Massachusetts, have invented a new and useful Narrow-Ware Loom, of which the following is a specification.

This invention relates to a narrow ware loom and particularly to improved devices 10 for supporting the rolls of ribbon or other material woven by the loom. It has been customary to wind these rolls upon shafts of considerable length and it was necessary to take out the entire shaft to remove any one 15 of the rolls mounted thereon.

It is the general object of my invention to provide a construction by which the rolls are independently mounted, thus permitting convenient removal or replacement of any 20 desired roll.

A further object of my invention is to provide improved means for holding a roll, permitting also very easy removal of the roll from its roll holder.

25 With these general objects in view, important features of my invention relate to novel means for securing and operating the roll holding fingers and to a novel device for axially positioning the roll holding support in the loom.

30 My invention further relates to arrangements and combinations of parts which will be hereinafter described and more particularly pointed out in the appended claims.

35 A preferred form of my invention is shown in the drawings in which—

Fig. 1 is a partial front elevation of the takeup mechanism of a narrow ware loom;

40 Fig. 2 is a sectional side elevation, taken along the line 2—2 in Fig. 1;

Fig. 3 is an enlarged front elevation of one of the roll holders;

Fig. 4 is a side elevation thereof, taken in the direction of the arrow 4 in Fig. 3;

45 Fig. 5 is a plan view of one of the blanks from which the positioning devices are formed;

Fig. 6 is a sectional elevation of one of the positioning devices;

50 Fig. 7 is a sectional elevation of a modified form of roll holder, taken along the line 7—7 in Fig. 8; and

Fig. 8 is a left hand side elevation of the parts shown in Fig. 7.

Referring to the drawings, I have shown 55 a portion of a loom frame 10 in which is rotatably mounted the usual takeup roll 11. Idler pulleys 12 are mounted on swinging arms 13 and the ribbon or other material R passes under the roll 11 and over the roll 60 12 from which it is led downward to the roll holder.

Each roll holder comprises a hub 14 (Fig. 65 3) mounted on a stud 15 secured in the upper end of an arm 16 loosely pivoted upon a fixed shaft 17. The axial position of the roll holder relative to the takeup roll 11 and shaft 17 requires occasional adjustment and for this purpose the arms 16 are positioned 70 lengthwise on the shaft 17 by the adjustable holding devices 18 shown in detail in Figs. 5 and 6.

Each holding device 18 comprises a single 75 piece of sheet material, preferably spring steel, first blanked out as shown in Fig. 5 and provided with two openings 19 slightly larger than the shaft 17. The blanks are then bent to the form shown in Fig. 6 and are slipped over the shaft 17 with one of the arms 16 held between the two parts of each 80 holding device. When the sides of the device 18 are pressed together to substantially parallel position the device and arm may be freely moved longitudinally of the shaft 17, but when released the sides swing apart and 85 grip the shaft. I have thus provided an extremely convenient means for axially adjusting and holding the arms 16 on the shaft 17.

The hubs 14 are each provided with a 90 circumferential groove 20 and with a plurality of transverse notches 21 intersecting the groove 20. The roll holding members comprise a plurality of fingers 22, each preferably formed of a single piece of sheet 95 metal, having one end bent under to form a cam surface 23 and having a V-shaped offset projection near the opposite end. The fingers are positioned in the notches 21 of the hub and are secured against displacement therefrom by a binder shown herein as a wire 25 disposed in the bottom of the groove 20.

A collar 26 is slidably mounted on the

stud 15 and when moved to the left in Fig. 3 moves the fingers from the dotted line to the full line position in said figure. When in the latter position the fingers are well adapted to form the foundation for a roll of ribbon, tape or other narrow material which may be wound directly upon the fingers as indicated in Fig. 3 or may, if preferred, be wound upon a tube as indicated in Fig. 7. 10 When the roll is completed, the collar 26 may be pushed inward, allowing the fingers 22 to collapse, and freeing the roll for easy removal.

The construction shown in Figs. 7 and 8 is particularly adapted for supporting rolls wound upon tubes and comprises a roller 30 rotatable upon a stud 31 and having a circumferential groove 32 near one end thereof. Transverse slots 33 and 34 are 15 formed at one point in the circumference and a resilient metal finger 35 is held from displacement in the slots by a binder 36 as previously described. The middle portion of the finger 35 rests upon a projection 37 between the slots 33 and 34 and the outer end of the finger 35 is preferably provided with a spur 38 adapted to extend into the tube 39 and prevent relative rotation thereof. When the material and tube are to 20 be removed, the projecting outer end of the finger 35 may be depressed to withdraw the spur 38 from the tube. This construction is desirable when a tube is used as a foundation for the roll but does not permit as 25 easy removal of the roll when no tube is used.

The roll holder in each case is preferably rotated by an elastic friction band 40. The takeup roll 11 and the hub 14 are so proportioned that the roll will be rotated at sufficient speed to wind up the material at the smallest diameter of the roll. As the roll increases in size, the elastic band 40 slips through the groove 20, thus permitting lost motion between the roll and band and turning the roll only fast enough to wind up the ribbon delivered thereto.

A weighted arm 41 preferably extends rearwardly from each arm or support 16 and normally holds the parts in the position shown in Figs. 1 and 2 but permits any roll to be swung forward for inspection or removal.

Having thus described my invention, the use and advantages thereof will be readily apparent and it will also be seen that changes and modifications can be made therein by those skilled in the art within the spirit and scope of my invention as set forth in the claims. Therefore, I do not wish to be otherwise limited to the details herein disclosed but

What I claim is:—

1. In a narrow ware loom, a fixed shaft, a plurality of arms mounted to swing freely

on said shaft and longitudinally adjustable thereon, means to hold each arm in adjusted longitudinal position, and a roll holder rotatably mounted on each arm.

2. In a narrow ware loom, a fixed shaft, a plurality of arms mounted to swing freely on said shaft and longitudinally adjustable thereon, means to hold each arm in adjusted longitudinal position, a roll holder rotatably mounted on each arm, and means to rotate said roll holders.

3. In a narrow ware loom, a fixed shaft, a plurality of arms mounted to swing freely on said shaft and longitudinally adjustable thereon, means to hold each arm in adjusted longitudinal position, a roll holder rotatably mounted on each arm, and means yieldingly retaining said arms in normal position.

4. In a narrow ware loom, a plurality of roll holders, a separate movably mounted support for each roll holder, a shaft on which said supports are slidably and rotatably mounted, and separate means to position each support axially on said shaft.

5. In a narrow ware loom, a plurality of roll holders, a separate movably mounted support for each roll holder, a shaft on which said supports are slidably and rotatably mounted, and separate means to position each support axially on said shaft, said means comprising a substantially U-shaped clip for each support, the sides of said clip being outwardly inclined when free and having openings therethrough for said shaft.

6. In a narrow ware loom, a roll holder comprising a hub having a circumferential groove and an axially extended notch, a holding finger seated in said notch and extending across said groove, and a binder in said groove preventing displacement of said finger.

7. In a narrow ware loom, a take-up roll, a plurality of cloth rolls located adjacent the take-up roll and having their axes normally in substantial alignment, and individual mountings for said cloth rolls permitting each roll to be moved independently out of alignment with the other rolls.

8. In a narrow ware loom, in combination, a tube, a driven roll on which said tube is supported, said roll having an axially extended groove and a circumferential recess, a tube driving member mounted in said groove and yieldingly engaging said tube, and holding means for said member positioned in said circumferential recess.

9. In a narrow ware loom, in combination, a tube, a driven roll on which said tube is supported, said roll having an axially extending recess with a raised intermediate portion, and a resilient arm secured at one end in said recess and also engaging said intermediate portion, the free end of said

arm yieldingly engaging and driving said tube.

10. In a narrow ware loom, in combination, a tube, a driven roll on which said tube is supported, said roll having an axially extending recess with a raised intermediate portion, and a resilient arm secured at one end in said recess and having its

middle portion engaged by said raised portion, the free end of said arm having a 10 spur yieldingly engaging said tube to drive the same.

In testimony whereof I have hereunto affixed my signature.

ELBRIDGE R. HOLMES.
